UNITED STATES PATENT OFFICE.

EUGENE MUNGER, OF BIRMINGHAM, ALABAMA, ASSIGNOR TO CONTINENTAL GIN COMPANY, OF BIRMINGHAM, ALABAMA, A CORPORATION OF DELAWARE.

VALVE MECHANISM FOR HYDRAULIC PRESSES.

1,292,014.

Specification of Letters Patent. Patented Jan. 21, 1919.

Application filed July 15, 1918. Serial No. 244,910.

To all whom it may concern:

Be it known that I, EUGENE MUNGER, a citizen of the United States of America, residing at Birmingham, in the county of Jefferson and State of Alabama, have invented certain new and useful Improvements in Valve Mechanism for Hydraulic Presses, of which the following is a specification.

- 10 This invention relates to hydraulic cotton trampers, baling presses and the like, and has for its object to perfect the automatic operation of the trumper platen and to so control the hydraulic valve mechanism that 15 the apparatus will operate with ease and reliability and without the creation of excessive pressures in the valve mechanism or the causing of severe jolts or jars to the press or piping system.
- 20 My invention contemplates no change in the press itself or in the type of press cylinder or platen that may be employed but is addressed more particularly to the hydraulic valve mechanism and the means employed 25 for its automatic control. To obtain the desired functioning of the hydraulic valve mechanism it is desirable that the distribution valve should be designed to avoid the trapping of the hydraulic pressure and the 30 creation therein of abnormal fluid pressures. Such a distributing valve mechanism while disclosed in this application forms the subject matter of a separate application Serial No. 210,951, filed January 8th, 1918.

- 35 The valve mechanism described in my said application comprises a four-way distributing valve under control of which the hydraulic pressure is delivered to and exhausted from the press cylinder and also a 40 by-pass valve automatically controlled by the trumper and having for its object the by-passing of the hydraulic fluid back to the pump when the press platen reaches the end of its stroke to prevent the building up of 45 high pressures in the cylinder and piping system.

One object of my present invention is to

improve the mechanism for effecting the automatic operation of this by-pass valve to the end that it will function at the end of 50 both the up and down strokes of the platen plunger and that it will be opened gradually on the down stroke of the plunger and automatically released so as to permit it to close and develop a pressure in the cylinder sufficient to raise the platen so that the latter's 55 return stroke may be automatically accomplished. It will be obvious that if all functions of this by-pass valve are automatic and controlled by the direct movement of 60 the platen itself, the by-pass valve when opened by the descent of the platen would remain open unless closed by hand, and while open would prevent the delivery of sufficient pressure to lift the platen plunger. 65

A further object of my invention is to give the distributing valve a slow movement as it reverses the pressure at the bottom of the platen plunger stroke, as I have found that a rapid throw of the distributing valve, when 70 controlling the high pressures in the press cylinders, is productive of severe jolting and jarring of the whole press and its distribution piping system.

A further object of my invention is to simplify the mechanism for controlling the reversal of the distributing valve responsive to the movements of the platen of the press box and to this end I contemplate the employment of lost-motion connections in the 75 operating mechanism which imparts the slow movement to throw the distributing valve in one direction and a spring and latch which will operate responsive to the filling of the press box to reverse the distributing 80 valve and restore it to the direct control of its slow moving operating mechanism which will accomplish its return stroke when the platen reaches the end of its down stroke.

My invention also comprises the various 85 details of construction and arrangements of parts which are hereinafter pointed out in the appended claims and which in their preferred embodiment only are illustrated in

the accompanying drawings which form a part of this specification, and in which:—

Figure 1 is a perspective view partly broken away of the hydraulic trumper press for baling cotton.

Fig. 2 is a plan view of Fig. 1.

Fig. 3 is a diagrammatic view illustrating the several parts of the valve operating mechanism and fluid pressure circulating system in outline.

Fig. 4 is a detail perspective view of the valve operating mechanism with the gear case cover removed.

Fig. 5 is a front elevation of the gear case with the cover removed and the gear in neutral position.

Fig. 6 is a sectional view taken on the line 6—6 of Fig. 5.

Fig. 7 is a detail view in side elevation of the operating mechanism for the by-pass valve when the platen is in its lowered position, the by-pass valve being shown in vertical section.

Fig. 8 is a partial sectional view taken on the line 8—8 of Fig. 7.

Similar reference numerals refer to similar parts throughout the drawings.

I have illustrated my invention in connection with a hydraulic trumper press mechanism comprising any standard type of press box 1 having above it an outwardly swinging apron 2 suspended by hanger bars 3 from hinge hooks 4 mounted on an I-beam 5 or like member forming part of the overhead frame work. This apron is adapted to be pressed outwardly by the cotton when the press box is filled in the manner well understood in this art by any suitable mechanism (not shown), and the cotton is adapted to be compressed in the press box by a vertically reciprocable platen 6 which is suitably connected to a piston rod 7 operated by a piston which reciprocates in a vertical cylinder 8 suitably mounted on the I-beams 5 and having a fluid pressure supply pipe 9 leading from its top to a distributing valve casing 10 and a like pipe 11 leading from its bottom to said valve casing. Fluid pressure is supplied to the valve casing 10 from any suitable pump 12 flowing therefrom through pipe 13 past check valve 14 to a pipe 15 entering the bottom of the distributing valve mechanism and returning normally through the exhaust pipe 16 to the tank 16^a. A lever 17 is pivotally mounted in a bearing bracket 18 and is so hung that its upper end is in position to come in contact with a trigger 19 and its lower end to come in contact with the apron 2, when the latter has been pushed out by the pressure of cotton fed to the press box. When this occurs, the trigger which is mounted on the pivot 20 (Fig. 2) will be lifted from in front of the collar 21 which is mounted on the outer end

of a valve stem 22 which serves to operate the distributing valve in the casing 10. A detailed description of this valve and its casing is omitted as the same forms the subject-matter of a pending application aforesaid, it being sufficient to say that any four-way valve structure may be used which will deliver fluid pressure from pipe 13 to the pipe 9 or 11 and return the exhaust fluid to 16.

The valve stem 22 has a block 23 attached thereto and to this block is connected a lever 24 pivoted on a bearing 24^a carried by the plate 25 which is mounted on and rigidly attached to the I-beams 5 and spans the latter. A spring 26 is interposed between the block 23 and a casting 27 which is adjustably and rigidly secured to the plate 25 in overhung relationship by bolts 28 working in slots 29 in the latter plate. The casting 27 has a vertical flange 30 surrounding its side edge toward the valve and also its outer edge. The outer end of this flange is outwardly to receive the pivot bolt 20 on which the trigger 19 is fulcrumed. A suitable opening is provided in this flange to receive and guide the valve stem 22, this opening being too small to permit the passage of the collar 21. When the machine is set up to start with the valve mechanism in position shown in Figs. 2 and 3, the pressure is in pipe 11 and the spring 26 is compressed and is held under compression by the trigger 19 engaging the collar 21. As soon as the pressure of the cotton moves the apron 4 sufficiently to cause the lever 17 to rock the trigger 19 and release the collar 21, the spring will force the valve stem to the right to quickly reverse the valve and direct the pressure into pipe 9 while opening pipe 11 to the exhaust. At the same time the lever 24 will be moved about its pivot 24^a, causing its free end to shift from the right to the left hand end (Fig. 2) of a slot 31 in a bar 32. A safety lever 33, pivoted for vertical movement in bearings 34 on the plate 25, is normally held out of position to engage the block 23 by a tension stirrup 35 which is locked to the press in the manner well understood in this art. When this stirrup is taken off the press, which is necessary to turn the press box, the lever 33 is balanced so that its weighted head will fall between the block 23 and the valve casing 10, thus preventing the valve stem 22 being moved by accident until the press box is in proper position and the stirrup is again attached thereto. The gear case 37 is rigidly connected to the bar 32 and within the gear case is a pinion 38 mounted on a shaft 39 having on its outer end without the gear case a beveled gear 40 meshing with a beveled gear 41 on a counter-shaft 42 which has fast thereon a sprocket gear 43 which is continu-

ously driven from any suitable source of power by a chain 44. The shaft 42 is mounted on bearing brackets 45 bolted to a plate 46 which in turn is bolted to the adjacent I-beam 5. Bearings 47 for the shaft 39 are also bolted to the plate 46. A casting 48 is rigidly secured to the gear case and projects beyond the same opposite to and in line with the bar 32 and at its free end this casting 10 48 is provided with an elongated head having therein the vertically elongated slot 49 in which an arm 50 on the cam 51 is slidably engaged, the arm carrying preferably a bearing pin 52 which travels in the slot 49. 15 The cam 51 is mounted in suitable overhung bearings 53 on the plate 46 and is provided with a slot 54, the straight end portions of which lie substantially at right angles to each other and are joined by a curved neck 20 struck on an arc concentric with the cam's axis.

Referring to Figs. 4, the upper end of the slot 54 is disposed substantially closer to the axis of the cam than is the lower 25 end of the slot and my object in thus arranging the slot is to produce thereby a vertical adjustment for the end of the lever 55 which has a bearing pin 56 working in the slot. This lever 55, as will be seen more 30 fully in Fig. 7, is a floating lever since its only fulcrum is formed by a pin 57 at the top of the link 58, which at its lower end is pivotally mounted on the stem 59 of a by-pass valve 60. The other end of the lever 35 55 is bent horizontally at 61 to project into the path of a lug 62 carried by a trip block 63 which is secured by set screws 64 on a rod 65 that is vertically disposed and mounted to reciprocate with the press platen 6. 40 The trip block is so disposed relatively to the floating lever 55 that it will engage and depress the near end of the latter only at the completion of the down stroke of the press platen. This operation is shown taking 45 place in Fig. 7 and it will there be observed that the cam 51 operating as shown in full lines, Fig. 7, on the far end of the lever 55 is in position to hold that end of the lever in a lowered position, and it thus forms a 50 fulcrum about which the lever as a whole swings when engaged and depressed by the trip block lug 62. This compression of the lever 55 results in forcing the by-pass valve 60 from dotted to full line position, Fig. 7, 55 thereby by-passing the fluid flowing to the valve mechanism through pipe 13 so that it is shunted through a pipe 65, by-pass valve casing 66 to a pipe 67 whence it returns to the pump tank 16. This opening movement of the by-pass valve compresses a 60 spring 68 which will close the valve as soon as either end of the floating lever 55 is released.

The trip block 63 carries a bracket 69 ar-

ranged at right angles to the lug 62 and having bolted thereto a vertically disposed elongated trip block 70, the ends of which project above and below the bracket 69 and have reversely sloping faces disposed toward a lever 71 pivotally mounted on a bearing bracket 72 so that it will rock in a vertical plane. The lever carries a crank 73 to which a pull rod 74 is connected at one end while its other end is connected to a bell crank lever 75 pivoted on a horizontal bearing bracket 76 and carrying at its upper end a roller 77, see Fig. 5, which engages the underside of the gear case 37. The trip block 70 is disposed so that its under beveled end will engage the lever 71 in advance of the lug 62 engaging the floating lever 55 and the block 70 is adapted to follow down and continue to depress the lever 71 until the platen 6 reaches its extreme lowered position. A coil tension spring 78 is interposed in the pull rod 74 so that it will act yieldingly to lift the gear case relatively to the stationary constantly turning gear 38 therein. This movement of the gear case will bring into mesh with the gear 38 the lower portion of its rack teeth 79 so that the gear 38 will act to move the gear case first in a direction to pull the bar 32 away from the lever 24 until the latter is engaged by the left hand end of the slot 31 (see Fig. 3), 85 whereupon the further movement of the gear case in the same direction acts to shift the valve rod 22 to the left, compressing spring 26, reversing the valve and moving the shoulder 21 beyond the latch 19 which 90 drops into position behind the same, whereupon the gear 38 reaches the end of the lower rack teeth 79, travels around the curved rack sector and engages the upper rack teeth to return the gear case bar 32 to initial position, as shown in Fig. 3. As seen in Fig. 6, the gear case 37 is left open on its side toward the gear 40 which drives the shaft 39. Bolted to the opposite side of the gear case is a box plate 80 to which the parts 32 and 48 are preferably attached and this plate has along its horizontal center line a guide flange 81 spaced equi-distantly between the upper and lower rack sections and stopping short of the ends of the gear 110 case. A reduced extension 82 of the shaft 39 projects through the gear 38 and is adapted to travel over or under this guide flange 81 which thereby serves to hold the rack and gear 38 in positive engagement 115 during the forward and reverse shifts of the gear case. The gear case 37 is thus moved slowly in the manner described to effect a reversal of the distributing valve and it carries with it the casting 48, and by the 120 co-operation of the slot 49 in the latter and the arm 50 on the cam 51, the latter is rocked from full to dotted position (Fig. 7).

When this rocking movement starts, the end 61 of the lever 55 is held depressed by the trip lug 62, and the initial rocking movement of the cam 51, by reason of the shape 5 of its slot 54, will give a further depression to the right hand end of the lever 55, causing it to more fully open the by-pass valve 60 so as to insure a low pressure in the piping before the reversing operation of the 10 valve takes place. The continued movement of the cam 51 serves to raise the lever 55 to its dotted line position, Fig. 7, thus closing the by-pass valve 60 and permitting the pressure to build up in the valve casing 15 10 and to flow through pipe 11 into the lower end of cylinder 8 and raise the platen. As the platen rises, the lug 62 releases the floating lever so that the return of the cam 51 to its full line position with the return 20 25 of the gear case will be without effect on the by-pass valve by reason of the fact that the lever 55 will then have no fixed fulcrum and can freely assume its initial position ready to be again engaged and depressed by the trip block 63.

When the platen reaches the top of its stroke it will engage a screw 83 in the outer end of a lever 84 pivoted on a horizontal bearing bracket 85 and pivotally connected 30 to the pin 86 which connects the lower end 35 of link 58 to the upper end of the by-pass valve stem 59. A link 87 pivoted on this bearing 85 is also connected to the pin 57 which pivotally connects the top of the link 58 to the floating lever 55, thus furnishing a 40 rocking support which will confine the floating lever 55 to the desired path of travel throughout its movements. When the platen thus moves the lever 84, it depresses 45 and opens the by-pass valve 60 and by-passes the fluid in the manner described, the platen meanwhile being held in raised position by the action of the check valve 14 on the pressure in the pipes 15 and 11, and the platen 50 stays in raised position until the apron 2 is tripped responsive to the filling of the press box with cotton, whereupon the latch 19 is tripped, the spring 26 snaps the valve stem 22 to reverse the distributing valve 55 and pressure is admitted to the top of the cylinder and exhausted from the bottom of the cylinder so that the downward or pressure stroke of the platen results. At the completion of this stroke the agencies 60 described will first partially and then completely by-pass the fluid so as to prevent abnormally high pressures being created in the distribution system while the slowly acting gear case 37 moves to reverse the distributing valve, whereupon the pressure is diverted to the lower end of the cylinder and exhausted from the upper end and the platen automatically rises. The trip block 63 and the screw 83 are adjustable so as to

obtain the desired timing for the trip actions.

The gear case 37 is typical of any slow moving reversing mechanism which can be automatically started and stopped under control of the platen, and the slotted bar 70 32 is typical of any lost-motion connection between the gear case and the valve setting lever 24 which will provide ample time for opening the by-pass valve prior to reversing the distributing valve so that this will not 75 occur in the presence of high pressure and also so that the reversing movement of the valve at the completion of the pressure strokes will be effected slowly as contrasted with the rapid reversal permitted by the 80 action of the released spring 26 at the completion of the up stroke of the platen.

Having thus described my invention, what I claim as new and desire to secure by Letters Patent, is:—

1. In a hydraulic trumper press, a cylinder and its piston, a platen operated by the piston, a fluid pressure distributing system for the cylinder comprising a distributing valve and a by-pass valve to short circuit 90 said distributing valve, and mechanisms automatically responsive to the completion of the platen's power stroke for shifting the distributing valve and temporarily opening the by-pass valve.

2. In a hydraulic press, a reciprocable platen, a power cylinder having its piston operably connected to said platen, a distribution system for the fluid pressure comprising a distributing valve for the cylinder and a 100 by-pass valve arranged to short circuit the distributing valve and cylinder, and platen controlled automatic mechanisms effective at the completion of the platen's power stroke to reverse the distributing valve and 105 open the by-pass valve during said reversal.

3. In a hydraulic press, a platen, a power cylinder having a piston operatively connected to said platen, a distribution system for the fluid pressure comprising a distributing valve for the cylinder and a by-pass valve arranged to short circuit the distributing valve, and platen controlled automatic mechanisms effective at both ends of the platen's stroke to open said by-pass valve 110 and reverse the distributing valve, and means responsive to the filling of the press to restrain the reversal of the distributing valve at the completion of the platen's up stroke.

4. In a hydraulic trumper press, a cylinder and its piston, a platen operated by the piston, a fluid pressure distributing system for the cylinder comprising a distributing valve, a by-pass valve to short circuit said 125 distributing valve, and mechanisms automatically responsive to the platen at the completion of its power stroke for operating

- the by-pass valve and shifting the distributing valve to start the platen on its return stroke, said mechanism for shifting the distributing valve comprising means adapted 5 to impart a slow reversing movement to said valve.
5. In a hydraulic press, a platen, a power cylinder having a piston operatively connected to said platen, a distribution system 10 for the fluid pressure comprising a distributing valve for the cylinder and a by-pass valve arranged to short circuit the distributing valve, platen controlled automatic mechanisms effective at both ends of the platen's 15 stroke to reverse the distributing valve, and means responsive to predetermined conditions to restrain the reversal of the distributing valve at the completion of the platen's return stroke, the automatic mechanism which 20 reverses the distributing valve at the completion of the platen's power stroke comprising a driving element and an intermittently operable driven means adapted to impart a slow reversing movement to said distributing 25 valve and a platen operated trip mechanism controlling the intermittent operation of said driven means.
6. In combination with a hydraulic press having a cylinder and a platen operable 30 thereby, a pressure fluid distributing system comprising a distributing valve for the cylinder, and operating mechanism for said valve comprising a constantly rotating driven element, a reciprocable element 35 driven thereby, means automatically operable at the completion of the platen's power stroke to connect said driving and driven elements, means to automatically disconnect said driving and driven elements at the 40 completion of the reciprocation of the driven element, a lost-motion operating connection between the driven element and distributing valve, and automatic valve means in said fluid distributing system to short circuit 45 said distributing valve during its operation by said driven element.
7. In a hydraulic trumper press, a cylinder and its piston, a platen operated by the piston, a fluid pressure circulating system 50 for the cylinder comprising a distributing valve, a by-pass valve to short circuit said distributing valve, mechanisms automatically controlled by and responsive to the platen at the completion of its power stroke 55 for reversing the distributing valve and opening the by-pass valve during such reversal, said mechanism for operating the distributing valve comprising means adapted to impart a slow reversing movement to 60 the distributing valve, latch controlled spring means which are set by said reversing movement of the distributing valve, and means responsive to the return stroke of the platen and the recharging of the press

to free said spring means to impart a quick 65 reversing movement to said distributing valve.

8. In combination with a hydraulic trumper press comprising a cylinder and its piston, a platen operable by said piston, a fluid pressure distribution system comprising a distributing valve, and automatic mechanism controlled by the movement of the platen at the completion of its power stroke for reversing said distributing valve, 75 said mechanism comprising a transmission means adapted to impart a slow gradual movement to said distributing valve to reverse it and start the platen on its return stroke. 80

9. In a hydraulic trumper press, a press cylinder, its piston and a press platen operable thereby, a fluid pressure distributing system for the cylinder comprising a distributing valve, a mechanism for automatically reversing said valve at the completion of the platen's power stroke comprising a constantly rotating gear, a gear case comprising a segmental gear normally out of mesh with said rotating gear, means 90 controlled by the descending platen to bring said gears into mesh, and means to hold the gears in mesh until the gear case has completed its cycle of movement, a lever for shifting the distributing valve, means 95 movable with the gear case which engage and move said lever in one direction only to reverse said valve with a slow movement, a spring opposing and which is compressed by said reversing valve movement, a latch holding said compressed spring in restraint, and means responsive to the recharging of the press to trip said latch and release said spring to operate the reversing valve, as and for the purposes described. 100

10. In a hydraulic trumper press comprising a press cylinder, a piston and a platen, a fluid pressure distributing system which includes a distributing valve for the cylinder, an automatic valve operating 110 mechanism comprising a lever coupled to the valve, a spring opposing that movement of the valve which reverses it at the completion of the platen's power stroke, a bar having a slot in which the free end of 115 said lever works, a segmental gear to reciprocate said bar, a driving gear adapted to reciprocate the segmental gear, mechanism controllable by the descending platen to bring said gears into mesh, means to hold the gears in mesh until the segmental gear completes its cycle of movement, said lever being operable in one direction by said slotted bar to reverse said valve and compress said spring, latch means to hold 120 the valve in said reversed position with said spring compressed, said slot being adapted to permit the free return to initial 125

- position of said lever, and mechanism responsive to the recharging of the press for releasing said latch mechanism to permit said spring to shift said reversing valve, substantially as described.
11. In a hydraulic trumper press, a press cylinder and its piston, a fluid pressure distribution system comprising a distributing valve and a by-pass valve to short circuit the fluid pressure relatively to said distributing valve, a press platen operable by the piston, automatic platen controlled mechanisms for reversing said distributing valve at each end of the platen's stroke, mechanism to restrain the reversal of the distributing valve at the completion of the platen's return stroke until the press has been recharged, automatic means to open the by-pass valve at the completion of the platen's stroke, and means, automatically responsive to the joint control of the platen and the mechanism for reversing the distributing valve at the completion of the platen's power stroke, to open and close said by-pass valve, substantially as described.
12. In combination with a hydraulic trumper press organization, comprising a cylinder, piston, platen and a fluid distribution system including a distributing valve and a by-pass valve adapted to short circuit said reversing valve, automatic mechanism for reversing the distributing valve at the completion of the platen's power stroke, mechanism requiring the joint action of said valve reversing mechanism and the platen to hold the by-pass valve open, and means to cause the by-pass valve to close at the completion of said reversal of the distributing valve.
13. The combination with a hydraulic trumper press, of a fluid pressure distribution system for the press cylinder comprising a distributing valve and a by-pass valve to short circuit the distributing valve, a floating lever for operating the by-pass valve, an element movable with the platen and adapted to engage said lever at the completion of the platen's power stroke, automatic mechanism controlled by the platen for reversing the distributing valve at the completion of the platen's power stroke, and an element movable with said mechanism and forming a shifting fulcrum which, in conjunction with said platen element, will hold the by-pass valve open only during said reversal of the distributing valve.
14. In a hydraulic trumper press, the combination with a press cylinder and platen operable thereby, of a fluid pressure distribution system for the cylinder comprising a distributing valve and a by-pass valve adapted to short circuit the distributing valve, automatic mechanism controlled by the descent of the press platen for reversing said distributing valve at the completion of the power stroke of the press, a cam movable by said mechanism, a floating lever operable jointly by said cam and said descending platen to open said by-pass valve, said cam assuming position at the completion of the power stroke of the press, a reciprocable cam movable by said mechanism, a floating lever operable jointly by said cam and said descending platen to open said by-pass valve, said cam assuming position at the completion of the reversing valve stroke which permits said by-pass valve to close, substantially as described.
15. In a hydraulic trumper press, the combination with a press cylinder and platen operable thereby, of a fluid pressure distribution system for the cylinder comprising a distributing valve and a self closing by-pass valve adapted to short circuit the distributing valve, automatic mechanism controlled by the descent of the press platen for reversing said distributing valve at the completion of the power stroke of the press, a reciprocable cam movable by said mechanism, a floating lever operable jointly by said cam and said descending platen to open said by-pass valve, said cam assuming position at the completion of the reversing valve stroke which permits the by-pass valve to close, substantially as described.
16. In combination, a hydraulic press cylinder, a platen operable thereby and a fluid pressure distribution system for the cylinder comprising a distributing valve and a by-pass valve adapted to short circuit the distributing valve, of automatic mechanism controlled by the platen and adapted to reverse said distributing valve at the completion of the platen's power stroke, a double cam operable by said mechanism, a floating lever having one end operable by the cam and its other end interposed in the path of an element on the descending platen and operable thereby about the cam as a fulcrum to open the by-pass valve, said cam being adapted upon resuming its initial position to permit the by-pass valve to close, and means to close the by-pass valve when released from the joint action of the platen element and cam.
17. In combination, a hydraulic press cylinder, a platen operable thereby and a fluid pressure distribution system for the cylinder comprising a distributing valve and a by-pass valve adapted to short circuit the reversing valve, of automatic mechanism controlled by the platen and adapted to reverse said distributing valve at the completion of the platen's power stroke, a cam operable by said mechanism, and a floating lever having one end operably engaged by the cam and its other end interposed in the path of an element on the descending platen and operable thereby about the cam as a fulcrum to open the by-pass valve, said cam being shaped as it moves in each cycle with said mechanism to at first further open the by-pass valve and then to close it.

18. The combination with a hydraulic press organization comprising a cylinder, piston, platen and a fluid pressure distribution system for the cylinder including a distributing valve and a self closing by-pass valve adapted to short circuit the distributing valve, a check valve between the by-pass and distributing valve, a stem for the by-pass valve, a lever having a fixed pivot connected at one end to the stem and having its free end adapted to be engaged and moved by the platen at the completion of its return stroke, a second lever connected to

said stem and having one end adapted to be engaged and moved by the platen at the completion of its power stroke, a shifting fulcrum for said second lever, and mechanism for reversing said distributing valve at the completion of the platen's power stroke and for shifting said fulcrum sufficiently to permit said by-pass valve to close at the completion of said reversing valve movement.

In testimony whereof I affix my signature.
EUGENE MUNGER.
